UNITED STATES PATENT OFFICE.

WILLIAM H. WILDER, OF BOSTON, MASSACHUSETTS.

OIL STOVE OR LAMP.

SPECIFICATION forming part of Letters Patent No. 450,547, dated April 14, 1891.

Application filed August 29, 1890. Serial No. 363,413. (No model.)

To all whom it may concern:

Be it known that I, WILLIAM H. WILDER, a citizen of the United States of America, residing at Boston, in the county of Suffolk and

5 State of Massachusetts, have invented certain new and useful Improvements in Oil Stoves or Lamps, of which the following is a specification, reference being had therein to the accompanying drawings.

10 My invention is an improvement upon oil or like stoves in which a zigzag flame is used—for instance, that shown in Letters Patent No. 420,221, granted to W. W. Batchelder, dated January 28, 1890. In said patent a zigzag flame-passage is employed in combination with a straight wick for the purpose of providing the largest possible surface of flame and obtaining a maximum amount of light and heat from a minimum consumption of oil and without 15 increasing the burning area of the wick.

It is the object of my invention to render the zigzag flame steady, to make it maintain its position and contour, and at the same time to prevent smoking and unevenness in the 20 height of the flame.

25 In the accompanying drawings, Figure 1 is a perspective view of the cone-plate and chimney, the cone and flame being shown in dotted lines. Fig. 2 is a transverse vertical section 30 through the stove, and Fig. 3 represents a chimney constructed to accomplish the objects of this invention.

35 In the use of the zigzag flame with the ordinary chimney it has been found that the contour and position thereof are easily affected by air-currents, which cause the flame to flit sidewise and assume an indefinite and uncertain form. This defective action gives rise to further objections, inasmuch as smoking is 40 likely to occur and the flame made uneven and unsteady.

45 I have found that by providing the chimney with an exit-opening above the flame corresponding substantially in shape to the contour of the flame that the air-currents induced within the chimney and constituting the upward draft will be controlled and properly directed to maintain the flame in correct position, and consequently preventing unsteadiness in its action.

In the drawings the burner cap or cone has a longitudinal flame-passage A of zigzag form, which is produced by the alternating deflecting-points 22 on opposite sides of the opening. Lips 24, as in the above-mentioned patent, are 55 employed opposite the square ends of the tongues or points 22, and the cap is curved, thus making the longer projections 22 of greater altitude than the lips, in order to make the flame spread upwardly as much as possible. The lips also serve to prevent the point of the flame from streaming up, and thus smoking. The flame-passage is slightly widened in its diagonal portions from its center to the ends to preserve the flame at a uniform 60 height. Under absolutely perfect conditions the flame-passage, as above described, will perform all the functions mentioned and good results will be obtained; but variations in the air-currents of the stove caused by outside influences or movements will destroy the perfect 65 action of the flame, and to obviate this and render the stove insensible to the disturbing influences I provide a chimney opening or throat above the zigzag flame corresponding in 70 shape and extent thereto. In Fig. 1 this throat-opening is shown at B, as formed in the lower plate 9 of the top grate, and not only does it conform to the general contour of the flame, but it has the same features as the flame-opening 75 in the cap—that is, the lips, the projections, and the increased width of the diagonal portions of the opening toward the ends. The flame spreads upwardly, and therefore the chimney-throat opening is made of greater extent laterally to accommodate this increased area. The chimney is made flaring upwardly 80 also to accommodate the spreading of the flame and prevent smoking or impinging of the flame against its walls.

85 It will be understood that the essential feature of my invention relates to the contour of the chimney-opening made to conform to the irregular or zigzag shape of the flame without regard to the precise location of the said opening, how it is formed, or how the irregular shape of the flame is made. It is essential 95 also that the chimney used in connection with the zigzag flaring flame be flared upwardly and outwardly, as above mentioned. The 100

chimney-opening may be formed by fluting or corrugating the chimney vertically, as in Fig. 3.

5 A heating-jacket may be used outside the chimney, if desired.

I claim as my invention—

1. In combination with a burner having a cone-plate with a zigzag flame-opening formed therein, a chimney extending upwardly from 10 said cone-plate and having a throat-opening above the cone corresponding in contour to the flame-opening, substantially as described.

15 2. In combination with a burner constructed to produce a zigzag flame, a chimney extending upwardly therefrom and having at a point above the burner a throat-opening corresponding to the shape of the flame, substantially as described.

20 3. In combination with a burner-cap having its flame-opening provided on its longitudinal walls with deflecting points or tongues alternating in position and the chimney having a throat-opening with corresponding points, substantially as described.

25 4. In combination with a burner constructed

to produce a zigzag flame, a chimney having a zigzag outlet, the diagonal portions of which are widened toward the ends of the burner, substantially as described.

5. In combination with a burner constructed 30 to produce a zigzag flame, a fluted chimney extending upwardly therefrom and fluted above the burner to correspond to the shape of the flame.

6. In combination with the burner constructed to produce an upward-spreading flame, a chimney having its walls flared upwardly and outwardly, substantially as described.

35 7. In combination with the burner constructed to produce a zigzag upwardly-flaring flame, a flaring chimney having a zigzag opening above the flame, substantially as described.

In testimony whereof I affix my signature in presence of two witnesses.

WILLIAM H. WILDER.
